[57] CLAIM

The ornamental design for a unitary half-sheet half-blanket, as shown and described.

DESCRIPTION

FIG. 1 is a top perspective view showing my new design for a unitary half-sheet half-blanket, the bottom view being a mirror image thereof;
FIG. 2 is an end elevational view thereof, the opposite end being a mirror image thereof;
FIG. 3 is a right side elevational view thereof; and,
FIG. 4 is a left side elevational view thereof.
